F. HAUSER

WINDOW

Filed Feb. 23, 1921

UNITED STATES PATENT OFFICE.

FREDERICK HAUSER, OF SAN FRANCISCO, CALIFORNIA.

WINDOW.

Application filed February 23, 1921. Serial No. 447,031.

To all whom it may concern:

Be it known that I, FREDERICK HAUSER, a citizen of the United States, residing at San Francisco, in the county of San Francisco and State of California, have invented new and useful Improvements in Windows, of which the following is a specification.

The present invention relates to window construction and more particularly to improvements in apparatus for mounting window sashes so that they will be reversible and both sides thereof may be easily washed and cleaned from the inside of a room or building.

15 The primary object of the invention is to simplify the construction and operation of reversible windows and to provide for simultaneously reversing the sashes of a multi-sash window, whereby in operating 20 one of the sashes of such a window to reverse the same all of said sashes will be likewise reversed, the reversing action being such that it may be easily and quickly effected and causes the sashes to be so disposed that ready and easy access thereto for 25 washing, may be had.

Another object of the invention is to provide reversing apparatus of such a nature that it may be easily attached to and used 30 in connection with standard sash and frame construction without necessitating any material changes in the construction of said sashes and frames, thus making possible an inexpensive conversion of the ordinary window into the reversible window of this invention.

The invention possesses other advantages 40 and features some of which, with the foregoing will be set forth at length in the following description where I shall outline in full that form of the invention which I have selected for illustration in the drawings accompanying and forming a part of the present specification. In said drawings I have 45 shown one form of the construction of my invention, but it is to be understood that I do not limit myself to such form since the invention as expressed in the claim may be embodied in a plurality of forms.

50 Referring to the drawing:—

Figure 1 is a vertical sectional view taken thru a window frame showing the apparatus of this invention applied thereto and in position assumed when the sashes are closed, 55 said apparatus being shown in side elevation.

Figure 2 is a vertical sectional view thru a window frame showing the sashes and apparatus of this invention in side elevation and in open position.

60 Figure 3 is a view similar to Figure 2 but showing the sashes reversed and broken in part.

Figure 4 is an enlarged fragmentary side elevation of the upper sash hinge shown 65 partly in section.

Figure 5 is a view of the hinge similar to Figure 4 but taken from the outside of, the window frame.

Figure 6 is a sectional view on line 6—6 70 of Figure 5.

Figure 7 is a sectional view taken on line 7—7 of Figure 1.

Referring to the preferred embodiment of the invention as shown in the accompanying 75 drawings, the window frame 1, having the customary vertical slide grooves 2, supports upper and lower sashes 3 and 4 respectively. Each sash has supporting arms 5 pivoted as at 6 to the side bars 7 thereof and as at 8 80 to plates 9 secured to the window frame 1, below the pivots 6. The pivots 6 are located between the upper ends and points centrally of the upper and lower ends of the bars 7 but nearer to the central points. The pivots 85 8 are located at points adjacent to which the lower ends of the sashes rest when the sashes are closed.

Both sashes are hingedly connected at their upper ends with sliding supports 10 90 which supports are mounted in the grooves 2 of the window frame. The upper ends of these supports 10 carry extensible members 11 held in place by screws 12 working in slots 13 in the members 10. Pivoted at one end to each of the extensible members as at 14 is a hinge plate 15. The plates 15 are pivoted as at 16 to plates 17 fixed to the sides of the bars 7 of the upper sash.

The plates 15 are provided with slots or notches 19 in which stop members 20 extend, said members 20 being carried on the extensible members 11. These stops engage with opposite ends of the slots or notches and limit the movement of the hinge plates in 105 both directions. The plates 17 are provided with outwardly directed lugs 21 which lie in the path of the lower edges of the hinge plates 15 at such angles as to cause the upper sash to be forced outwardly when 110 said lugs are engaged by said hinge plates and the latter are moved on their pivots.

Fixed to the members 10 adjacent to their lower ends are forwardly projecting plates 22 and the outer ends of these plates are pivoted as at 23 to plates 24, fastened in any suitable manner, to the outer sides of the bars 7 of the lower sash. The bars 7 of the sashes have portions 25 on their outer edges which portions are arranged to engage shoulders 26 on the frame 1. The lower edge of the upper sash has a depending weather strip 27 adapted to overlie the outer face of the upper part of the lower sash.

15 *Operation.*

To open the sashes the lower sash is pushed outwardly. The lower sash turns on the pivots 6 and 23 and the arms 5 for this sash swing outwardly at their upper ends 20 in a downward arc. Thus, the lower sash is lowered while the lower end thereof is swinging outwardly and this lowering causes a downward pull upon the members 10 in the grooves 2. As the members 10 are 25 pulled downwardly they pull downwardly on the inner ends of the hinge plates 15. Since the hinge plates 15 engage the lugs 21 on the upper sash and said lugs are angularly disposed as hereinbefore described, 30 the downward pull on the hinge plates 15 first causes a pivotal movement of these plates such that the upper sash will be forced downward and by reason of the arms 5 therefor will swing outwardly. The plates 35 15 move or rock on the pivot 14 only slightly, but sufficient to start the upper sash on its outward movement. When the stops 20 engage the rear ends of the slots or notches 19 the plates 15 are prevented from further 40 movement on their pivots 14 and remain stationary while the upper sash turns on the pivots 16, upon continued outward movement of the lower sash. It will thus be seen that both sashes may be moved to 45 any extent desired by pushing outwardly on the lower sash.

To reverse the sashes, for example, from the position shown in Figure 2, the upper edge of the lower sash may be grasped and pulled downwardly. This moves the members 10 downwardly and causes the upper ends of the sashes to be moved downward while the lower ends thereof move out and upwardly in an arc. This reverses the windows so as to bring them into 55 approximately a 45° angle, with the outer sides of the sashes uppermost and in position to be readily reached in the washing and cleaning thereof, (see Figure 3). To move the sashes back into normal position the normally upper edge of the lower sash is lifted upwardly until the lower edge is in position to be conveniently grasped and pulled inwardly to complete the closing 60 operation. The movement of the lower sash 65 is followed by similar movement of the upper sash.

By the peculiar combination of the sliding supporting members to which the sashes are hinged at their upper edges and the arms 70 5 pivoted to the sashes and window frame, the operation of the windows is made comparatively easy and convenient. The lugs 21 and plates 15 are arranged so as to prevent sticking or jamming of the window in 75 starting the opening or reversing operation.

I claim:—

A window comprising a frame, a member movable up and down upon said frame, a sash, an arm pivoted to a mediate portion 80 of a side of the sash and pivoted to the frame, a hinge connecting the sash with said movable member, another sash, an arm pivoted to said sash and the frame, a hinge plate pivoted to said member and the last-named sash which plate on initial 85 movement of said member when the sashes are in closed position, will move on its pivotal connection with the member and a stop for limiting such movement of said plate.

FREDERICK HAUSER.
